[57] **CLAIM**

The ornamental design for a slipper, as shown and described.

DESCRIPTION

FIG. 1 is a right side elevational view of a slipper showing my new design;

FIG. 2 is a top plan view thereof;

FIG. 3 is a rear elevational view thereof;

FIG. 4 is a front elevational view thereof;

FIG. 5 is a bottom plan view thereof; and,

FIG. 6 is a left side elevational view thereof.

The broken line showing of a numeral 24 on the sides of claimed design is for illustrative purposes only and forms no part of the claimed design. All other broken lines indicate stitching.
